UNITED STATES PATENT OFFICE.

HENRY S. FIRMAN, OF NEW YORK, N. Y., ASSIGNOR TO THE UNIVERSAL CONCENTRATING COMPANY, OF CAMDEN, NEW JERSEY.

INCINERATING-FURNACE.

SPECIFICATION forming part of Letters Patent No. 296,322, dated April 8, 1884.

Application filed May 3, 1883. (No model.)

To all whom it may concern:

Be it known that I, HENRY S. FIRMAN, a citizen of the United States, residing at New York, in the State of New York, have invented 5 certain new and useful Improvements in Calciners or Incinerating Furnaces, of which the following is a specification.

My invention relates to improvements more particularly on furnaces adapted for the recovery of soda-ash or similar materials in solution.

My improved furnace consists of three distinct sections—the fire-chamber, an igniting-furnace in rear of this, and a calcining or incinerating furnace. The fire-chamber is provided with a pendent bridge or curtain near its front end or center, and between the curtain and the front wall of the furnace I place a flue leading from the front of the fire-chamber to the igniting-chamber in the rear. The back of the fire-chamber is provided with a vertical series of trays, over which the material to be calcined is adapted to flow in its passage to the igniting-chamber. The front 25 wall and hearth of the igniting-chamber are preferably made of refractory fire-brick. To the back of the igniting-chamber is situated the final calcining-chamber, of the construction hereinafter more particularly specified.

30 In order that my invention may be more fully understood, I will proceed to describe it with reference to the accompanying drawings, in which—

Figure 1 is an axial section of the improved furnace. Fig. 2 is a transverse section of the fire-chamber on the line 2 2, Fig. 1. Fig. 3 is a transverse section of the calcining-furnace on the line 3 3, Fig. 1.

The body of my furnace, 1, is preferably of 40 brick, as shown. Within the bricked portion are included two chambers of the furnace—the fire-chamber 2 and the igniting-chamber 3. The grate is shown at 4, ash-pit at 5, and door at 6. At each side of the fire-chamber I locate three escape-flues, 7, which unite on each side at top in flues 8 8, which lead to the back of the furnace, where they unite and discharge at the stack or a flue, 9. Stretching midway of the furnace and dividing it into two chambers is a partition, 10, of refractory material.

In front of this partition is arranged a vertical series of trays, 11, inclined, so that liquid material flowing into the uppermost tray through pipe 12 from tank 13 will fall from one to another until it is discharged past the fire-bridge 14 onto the hearth 15 of the igniting-furnace 3. A damper, 27, between the fuel-furnace and igniting-hearth enables the partial or complete isolation of these two sections of the furnace. A fixed curtain or deflector, 16, of refractory material, is arranged in the front portion of the fire-chamber to deflect fresh air entering at the door 6 into the flue 17 at the top of the furnace. This flue leads centrally between the side flues, 8, back 60 into the igniting-chamber and discharges its contents of heated and nearly pure air onto the top of the heated material lying on the hearth 15. The heated products of combustion issuing from the fire-chamber through 65 passage 18 will, when fed by the oxygen from the flue 17, rapidly ignite the sap and other organic matter on the hearth 15. If at any time it be desired to cut off the supply of air passing through flue 17, the damper 28 at the 70 entrance thereof may be employed.

In practice the flues 7 are employed merely in starting the combustion in the furnace. When the fire is well under way, they are closed and the damper 27 opened and nearly 80 all the products of combustion thrown into the rear chambers of the furnace. The steam or vapor generated from the water which I constantly keep in the ash-pit, being decomposed by the intense heat from the chamber in the 85 first section of the furnace, evolves hydrogen gas. This combining with the oxygen supplied by flue 17 forms an oxyhydrogen flame of great heat. In conjunction with, or instead of this arrangement, I may employ in some cases a 90 blast to assist the combustion in the furnace. From the igniting-chamber the burning material is shoveled or discharged by suitable means onto the tight hearth 19 of a reversible or revolving furnace, 20. This consists of an elongated box or casing, square or circular in cross-section, supported by ways 21 on rollers or wheels 22.

Stretched from end to end of this furnace are two open hearths, 22 23, held to place by 95

a brace, 24, and having stretched between them a suitable sifter or screen, 25. A series of doors, 26, arranged along the lower edge of the furnace, allows the discharge of the completely finished material.

In some cases, instead of the calcining-furnace being placed horizontally, as shown, and arranged to discharge at the side through the doors 26, it may be inclined downwardly from the igniting-hearth in such manner that the rotation of the furnace itself shall continuously carry the material forward and discharge it completely incinerated at its lower end.

The operation of the apparatus is as follows: The alkaline or other solution, already partially evaporated, having been conducted or pumped into the tank 13, is led therefrom by pipe 12 into the uppermost of the trays 11, whence it flows gradually onto the hearth of the furnace 3, becoming ignited in its passage. Here the products of combustion, issuing in a highly-heated state through passage 18, impinge against the hydro-oxygen blast from flue 17, and being deflected downward still more thoroughly ignite the sap and other organic matter of the material on the hearth. The now freely burning material is shoveled or otherwise conducted onto the tight hearth 19 of furnace 20, where the calcining process is continued and completed, as follows: The furnace being turned in the direction of the arrow, by power or hand through suitable mechanism, the material, gravitating as the furnace turns, will at length reach and rest upon the open hearth 22. The furnace, being allowed to rest for a time in this position until the burning becomes less free, is then turned further, throwing the material through the breaking-sifter 25 onto the second open hearth, 23, where the burning will recommence with renewed force. The rotation of the furnace is continued till the organic matter is nearly or quite burned out.

Having thus described my invention, the following is what I claim as new therein and desire to secure by Letters Patent:

1. A calcining-furnace formed of contiguous chambers, substantially as hereinbefore described, which consists, first, of a fire-chamber, then an igniting-hearth at the rear end of said fire-chamber, and, finally, a calcining-chamber at the rear of the igniting-hearth, whereby the material is subjected to a furnace-heat gradually diminishing in intensity from

the point of admission to the point of delivery, 55 as and for the purposes set forth.

2. A calcining-furnace consisting of a stationary fire-chamber, a stationary igniting-hearth, and a revolving calcining-chamber, all arranged and adapted to graduate the intensity of the furnace-heat from a maximum at the point of admission to a minimum at the point of delivery, substantially as shown, and for the purposes set forth.

3. A calcining-furnace formed of contiguous chambers, substantially as herein described, which consist of a fire-box and igniting-hearth, located in such positions relatively to each other as to cause the products of combustion to be discharged through the material during its descent, and a calcining-chamber located at the rear of the igniting-hearth, as and for the purposes set forth.

4. A calcining-furnace having a suitable supply-tank connected with a series of evaporating-trays located in the fire-chamber, and adapted to effect a partial evaporation of the material during its descent to the incineration-hearth, as set forth.

5. The combination of fire-chamber having at back suitable heating-trays, igniting-hearth to the rear of the fire-chamber, and a flue for leading pure or nearly pure air in a heated state onto the igniting-hearth, substantially as set forth.

6. The combination of fire-chamber having the pendent curtain near its front, the igniting-hearth to the rear of the fire-chamber, and the flue leading from the front of the fire-chamber and discharging pure or nearly pure air onto the material on the igniting-hearth, substantially as set forth.

7. The combination of fire-chamber having the pendent curtain near its front or center, the igniting-hearth to the rear of the fire-chamber, and a flue leading from the front of the fire-chamber and discharging pure or nearly pure air onto the material on the igniting-hearth, substantially as set forth.

8. The combination, in the calcining-furnace, of two or more open hearths on the sides thereof, and having a screen or sifter stretching between the same, as specified.

H. S. FIRMAN.
